UNITED STATES PATENT OFFICE.

ELWOOD M. POWERS AND GEORGE W. HAGERTHEY, OF LINWOOD,
NEW JERSEY.

CLOTHES-LINE REEL.

SPECIFICATION forming part of Letters Patent No. 781,548, dated January 31, 1905.

Application filed October 2, 1902. Serial No. 125,689.

To all whom it may concern:

Be it known that we, ELWOOD M. POWERS and GEORGE W. HAGERTHEY, citizens of the United States, residing at Linwood, county of Atlantic, and State of New Jersey, have invented a certain new and useful Improvement in Clothes-Line Reels, of which the following is a specification.

Our invention relates to a new and useful improvement in clothes-line reels, and has for its object to provide a reel which is entirely inclosed, so as to protect the line from the weather when it is not in use; and a further object of our invention is to provide a spring which will automatically wind the line upon the reel when said line is released.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a perspective view of our improved-reel complete; Fig. 2, a vertical longitudinal section through the same; Fig. 3, a vertical cross-section through the reel.

A represents the casing, which may be of any suitable shape or design, but preferably constructed with an inclined roof or cover for the purpose of shedding rain. This casing is designed to be attached to a post, fence, or other support in any suitable manner, either permanently or removably. The casing A is partitioned off in three compartments (numbered 1, 2, and 3, respectively) by the two partitions B and C.

D represents a shaft extending through one side of the casing and also through the two partitions B and C and terminating a short distance beyond the partition B.

E is the reel, secured to the shaft D and located in the compartment 1. This reel may be made in any suitable manner; but as we have shown it in the drawings it consists of two cross-pieces F, which are formed with V-

shaped notches F' in their ends to receive the 50 line.

Secured to the shaft D and located in the compartment 2 is a gear-wheel G, which meshes with a second gear-wheel H, also located in the compartment 2 and secured to a shaft I, 55 which extends across the compartments 2 and 3 and is journaled in the partitions C and B and also one side of the casing A. To prevent any transverse movement of the wheels G and H, collars α on the shafts are interposed there- 6c between and the walls of the compartment 2. To this shaft I is secured one end of a flat coil-spring J, the other end of said coil-spring being secured to the casing at the point J'. Upon the outside of the casing and secured to 65 the shaft D is a ratchet-wheel K, and L is a pawl pivoted to the casing and adapted to engage said ratchet-wheel.

The operation of the device is as follows: The clothes-line M is wound upon the reel, and 70 when the clothes-line is fully wound the spring J is lax, or nearly so, and the outer end of the clothes-line extends through an opening formed through the front of the casing, as indicated at N, and may be formed into a knot 75 to prevent the same from entirely entering the inclosure. When it is desired to use the line, the outer end is grasped and pulled from off the reel, and the reel in turning will, through the gear-wheels G and H, wind up the spring J, 80 and when sufficient length of line has been strung upon the clothes-lines the outer end is secured in place and the pawl L, working in conjunction with the ratchet-wheel K, will keep the weight of the line and contents from 85 exerting any influence upon the reel; but when it is desired to rewind the line upon the reel it is only necessary to remove the line from its fastenings, and the spring J will then exert its influence and through the gear-wheels rotate the reel so as to wind the line upon the same.

Of course we do not wish to be limited to the exact construction here shown, as slight modifications could be made without departing 95 from the spirit of our invention.

Having thus fully described our invention, what we claim as new and useful is—

In a clothes-line reel, a casing having an inclined roof, two partitions within the casing dividing the space therein into three compartments, a shaft journaled in one side of the casing, and extending through and journaled in the sides of the middle compartment, two cross-pieces mounted on the shaft in the outer compartment, said cross-pieces having V-shaped notches in their ends, a second shaft 10 journaled in the opposite end of the casing and extending through and journaled in the walls of the middle compartment, a spring in the outer compartment of the second shaft for rotating said shaft, gear-wheels mounted on

the shafts in the middle compartments and 15 adapted to intermesh, collars on the shafts within the inner compartment interposed between the wheels and walls of said compartment and means for regulating the rotation of the shafts.

In testimony whereof we have hereunto affixed our signatures in the presence of two subscribing witnesses.

ELWOOD M. POWERS.

GEORGE W. HAGERTHEY.
